ATTORNEY.

UNITED STATES PATENT OFFICE.

EMMA KNAPP, OF DENVER, COLORADO, ASSIGNOR TO WILLIAM F. KNAPP, OF DENVER, COLORADO.

HASP LOCK.

1,403,252.

Specification of Letters Patent. Patented Jan. 10, 1922.

Application filed October 27, 1920. Serial No. 419,787.

To all whom it may concern:

Be it known that I, EMMA KNAPP, a citizen of the United States, residing at Denver, in the county of Denver and State of Colorado, have invented certain new and useful Improvements in Hasp Locks, of which the following is a specification.

This invention relates to improvements in hasp-locks and its primary object is to provide in association with the staple of a fastening of this character an adjustably mounted lock adapted to secure the hasp in its operative position thereon.

In the accompanying drawings in the various views of which like parts are similarly designated,

Figure 1 represents an elevation of the cooperating members of my improved hasp lock in its open condition;

Figure 2, a similar view showing the parts in their closed position;

Figure 3, a plan view of a modified construction of the fastening;

Figure 4, a side elevation of the same in the unlocked condition, and

Figure 5, a view similar to that of Figure 4 showing the parts of the modified form of my invention in their locking position.

Referring first to Figures 1 and 2 of the drawings, the reference characters 2 and 3 designate two related objects such as a door and its casing or a box and its lid, to which my improved hasp-lock is applied.

The hasp-lock consists of a staple 4 fastened on a base 5 by means of which it is secured to one of the objects, and a hasp 6 which is hinged to a plate 7 secured to the other object, in cooperating relation to the staple.

The staple base 5 has an extension 5^a for the movable support of the lock 8 which may be of any suitable construction to cooperate with the staple for the purpose of securing the hasp in place thereon.

The lock in the construction shown in the drawings consists of a housing containing the usual key-actuated mechanism for the projection and retraction of a shackle which in practice passes through the staple.

The means for mounting the lock on its support comprises a pair of parallel links 9 which at their ends are pivotally connected to correspondingly position knuckles formed respectively on the support and at the under side of the lock.

The end of the lock at which its shackle is located faces the staple when the fastening is in its unlocked condition as shown in Figure 1 of the drawings, and it will be apparent that by very simple manipulation the lock may be instantly adjusted to its operative position with relation to the staple as illustrated in Figure 2.

The modification of my invention shown in Figures 3 to 5 is, owing to its compactness of construction, particularly adapted for use on flexible objects such as the straps used for closing mail sacks and the like.

The lock support 5^b is in this form of the invention formed at an angle to the base plate of the staple, which is fastened at an end portion of the strap 10 to cooperate with the hasp connected at the opposite end of the same through the medium of a link 12.

The links 13 and 14 by which the lock is mounted on the support are of dissimilar lengths and they are pivotally connected to knuckles at the under side of the lock as in the first-described construction and to corresponding knuckles at the opposite ends of the support.

A spring 15 fastened to one of the links limits the movement of the lock away from the staple and a lever 16 fulcrumed on the pivot by which the other link is connected to the knuckle of the support, serves in the operation of the device to lift the hasp while the lock is being separated from the staple whereby to facilitate its removal.

One of the arms of the lever, to this end contacts with the under side of the moving lock as shown in Figure 4, while its opposite arm engages the under side of the hasp.

It will be seen that while in the construction shown in Figures 1 and 2 the lock moves linearly toward and from the staple, it is in the other form of the invention moved in an arc owing to the difference in length of the two links by which it is mounted on its support.

Having thus described my invention what I claim and desire to secure by Letters-Patent is:

1. A hasp-lock comprising in combination, a staple, a hasp cooperating therewith, a lock-support, and a lock having a link-connection with said support for its adjustment to and from the staple.

2. A hasp-lock comprising in combination, a staple, a hasp cooperating therewith, a

- lock-support, and a lock having a double link-connection with said support for its adjustment to and from the staple. 35
3. A hasp-lock comprising in combination, 5 a staple having a base-plate, a hasp cooperating with the staple, a lock support formed on the base-plate, and a lock having a link-connection with said support for its adjustment to and from the staple.
- 10 4. A hasp-lock comprising in combination, a staple, a hasp cooperating therewith, a lock-support, a lock adapted to operatively engage the staple, and two links pivoted to the support and to the lock for adjustment 15 of the latter to and from the staple.
5. A hasp-lock comprising in combination, a staple, a hasp cooperating therewith, a lock-support, a lock adapted to operatively engage the staple, and two links of unequal 20 lengths pivoted to the support and to the lock for adjustment of the latter to and from the staple.
6. A hasp-lock comprising in combination, a staple, a hasp cooperating therewith, a lock-support, a lock adapted to operatively engage the staple, and two parallel links pivoted to the support and to the lock for adjustment 25 of the latter to and from the staple.
7. A hasp-lock comprising in combination, 30 a staple, a hasp cooperating therewith, a lock-support, a lock having a link-connection with said support for its adjustment to and from the staple, and a lever engaged by

the lock to be moved about its fulcrum during movement of the lock away from the staple and having a lifting action on the hasp in its operative position on the staple. 35

8. A hasp-lock comprising in combination, a staple, a hasp cooperating therewith, a lock-support, a lock having a link-connection 40 with said support for its adjustment to and from the staple, and a lever fulcrumed on the support, and having an arm in the path of the lock and another arm extending alongside of the staple to lift the hasp. 45

9. A hasp-lock comprising in combination, a staple, a hasp cooperating therewith, a lock support, a lock adapted to operatively engage the staple, two links pivoted to the support and to the lock for adjustment of 50 the latter to and from the staple, and a lever fulcrumed to move about a pivotal axis of one of the links and having an arm in the path of the lock and another arm extending alongside of the staple to lift the hasp. 55

10. A hasp-lock comprising in combination, a staple, a hasp cooperating therewith, a lock-support, a lock having a link-connection with said support for its adjustment to and from the staple, and means for limiting 60 the movement of the lock away from the staple.

In testimony whereof I have affixed my signature.

EMMA KNAPP.
